DAVID M. MORPHY, OF DE KALB, ILLINOIS, ASSIGNOR TO UTICA HEATER COMPANY,
OF UTICA, NEW YORK, A CORPORATION OF NEW YORK.

WARM-AIR FURNACE.

Application filed June 16, 1923. Serial No. 345,723.

To all whom it may concern:

Be it known that I, DAVID M. MORPHY, United States citizen, residing in De Kalb, Illinois, have invented the following described Improvements in Warm-Air Furnaces.

The invention relates to air heating furnaces for dwellings and the like. Its principles are applicable to various types of air heating furnaces but are particularly suited for so-called return-flue-radiator heaters which are well known in the art, and the object is to admit supplemental air to the burning fire gases in such furnaces, in such way as to improve the combustion efficiency and therefore eliminate or reduce the production of smoke and so that this result can be obtained not only occasionally or with one grade of coal, but continuously and with bituminous coals of any of the several varieties that are sold in different parts of the country and which, as well known, differ very considerably in their smoke-producing propensities. The furnace design herein disclosed in illustration of the invention, is suited for easy smokeless operation on any of these coals as well as with other fuels and is also adapted by its general method of organization for prolonged and practically indefinite use without impairment, as by the burning out of the supplemental air-admission means or by unequal expansions and contractions and notwithstanding that the said means is devoid of water-back protection heretofore found more or less indispensable in supplemental air furnaces.

In the drawings:—

Fig. 1 is a vertical central elevation of a warm air furnace with parts shown in central section.

Fig. 2 is a top plan of the heater proper.

Fig. 3 is a horizontal section, enlarged, of the air-admission ring of Fig. 1.

Fig. 4 is a perspective thereof, and

Fig. 5 a perspective of a modified ring.

The furnace comprises a main enclosing shell or outer casing 1 adapted for connection at the bottom with a source of fresh air and at the top with a number of hot air pipes leading to the rooms to be heated, as customary. In the case of so-called pipeless furnaces the entrance for the air to be heated and for the heated air is through a floor radiator connected to the top of the casing 55 as will be understood by those familiar with

this art, but in either case the design of the casing is of no consequence to this invention. It is commonly made of sheet iron supported and braced by suitable interior framing and is commonly and preferably provided with a 60 cast metal front panel, 2, designed to accommodate the several entrances to the heater proper enclosed by it. The heater comprises a base or ash-pit section 3 provided with a conduit tunnel 4 extending to and preferably 65 through the panel front where it is provided with a door through which ashes may be removed and also with a damper for the entrance of the main supply of combustion-supporting air. The two fire-pot sections 5 70 are mounted one above the other on the ash-pit section and above the level of the grate 6, and the fire chamber dome 7 is mounted upon these sections and provided with a doorway or fuel feed conduit 8 extending 75 horizontally to or through the casing front where it is closed by the usual feed door. The dome 7 of the fire chamber tapers with a gradual taper, to a restricted outlet at its top which outlet is above the level of the fuel 80 feed doorway. All of the fire gases pass through this restricted outlet into the radiator which constitutes the top of the heater. The connection between the fire chamber and the radiator of the heater is formed by an 85 air-admission ring 9 which as herein shown is preferably a separately made part or structure fitted on its upper and lower sides to the bottom of the radiator and the top of the fire chamber, respectively, by means of a 90 circular mortise and tenon joint such as is commonly used between heater parts, the grooves of these joints being relatively wide with respect to their tenon members so as to accommodate differences in the thermal ex- 95 pansions of each part with respect to the others. The air-admission ring 9 is most simply made as a hollow, ring-form, one-piece casting having an inside diameter about equal to that of the restricted fire 100 chamber outlet and an outside diameter somewhat larger than the outside diameter of said outlet. Its inner wall is provided with one or more holes, and its outer wall is provided with a bossed opening adapted 105 to fit and support one end of a square air duct casting 10, the other end of which extends to the furnace front, directly over the fuel feed conduit, and is supplied with a door or damper 11. Under the pull of the 110

chimney, air is drawn directly from atmosphere through this duct and ring, supplemental to the air admitted through the ash-pit, and is distributed by the ring into the 5 fire gases issuing from the fire chamber, the condition and manner of such distribution being such as to produce the new results above stated and as will be later described.

The radiator is of common design and responds to the condition that air heating furnaces must be low in height in order that the 10 hot air pipes which lead from the top of the casing may have the necessary rise or upward slope. Consequently it is composed 15 of flues which are all arranged in a common level or horizontal plane and provided with a central, downwardly opening entrance part 12 which is herein termed the elbow of the radiator because this is the part which 20 is directly fitted to the air-admission ring and receives and turns fire gases from an upward into an horizontal direction of movement. From this elbow, the fire gases divide and flow reversely through the two 25 semi-circular flues 13 to the single fire gas outlet 14 located at the rear side of the radiator, but so far as concerns this invention, the path or shape of the flues of the radiator is quite unimportant. It is only 30 necessary that between the gas inlet or elbow 12 and the surrounding flue structure 13, there shall be present a ring-form air-duct section exposed to contact with the 35 current of partially heated air which flows upwardly along and over the surface of the fire dome 7. This current of air, together with the air drawn in through the duct 10, is relied on for keeping the air-admission ring 9, which projects into said current, 40 from acquiring an injurious temperature. It will be understood that the effect of supplemental air-admission, when properly designed stimulates the combustion so as to generate a most intense and white-hot 45 flame which is very apt to burn out the iron of the admission means unless precautions are taken against it. It is necessary, however, that the admitted air be well heated for mixture with the fire gases and 50 the problem of thus heating the air without endangering the iron has therefore been a difficult one. By gradually tapering the fire dome 7 and making its upper, outlet 55 part of about the same diameter as the radiator elbow, the construction is adapted to permit the rising air to flow freely and practically straight from the exterior of the fire chamber into the annular air passage through the radiator and further, 60 by locating the outer wall of the air ring 9 so that it is exposed to, or projects into this unobstructed air current, an effective but entirely safe temperature condition is obtained, and irrespective of other features 65 of this invention, this arrangement of the

parts represents an advance in the art of air heating furnaces of this type. It is easily distinguished from prior efforts in the same direction wherein the air-admission ring or passage is either contained 70 within the boundary of the outlet part of the fire pot or located behind or between abrupt shoulders, or in the waist of the structure so to speak, so that the upward air current cannot easily reach and cool 75 it, or else such rings have not been located at the most efficient point in the fire gas flow which is at the restricted junction between the fire chamber and the elbow 80 part of the horizontal ring-form radiator as above pointed out.

A clean out conduit 15 is formed on or connected to the radiator on its front side, extending to or through the panel front and there provided with a clean-out door 16. 85 When the radiator is formed of a single casting, as in the present case, it is reinforced by a vertical web 17 between the free end of the elbow and the outlet side of the ring-form flue. 90

Referring now to the air-admission ring, it will be observed that the perforations or openings 18 and 19 in its inner wall and as shown in Figs. 3 and 4, are non-symmetrically arranged. The openings 18 are round holes and the opening 19 is a relatively large square hole, and is located directly in line with the air-admission duct 10 while the round holes 18 are evenly spaced around the opposite side. The ring thus has a greater cross area for the delivery of air into the fire gases on one side than on the other and the side of greatest area is located on the side toward which the fire gases are turned by the elbow 12. 100 This disposition of the air-admission entrance means, as shown by Figs. 3 and 4, is preferable for the larger sizes of furnaces and produces the best mixing effect and the best combustion results. For smaller 110 sizes, wherein for example the interior diameter of the air-admission ring is not more than about six inches, the sole admission for the air is through the single hole 19 without any air holes on the opposite side, but in either case it will be noted, the ring presents a greater cross area for air-admission on one side than on the other, and in both cases the side of maximum area is on the side toward which the elbow 12 turns the gases, that is to say, 120 toward the front of the furnace in the form under description.

It is desirable, also, that the air duct 10 be located between the radiator, or the clean-out entrance thereof, and the fuel feed conduit, because both of these parts are heated by the fire gases and function to transmit heat to the air duct in suitable and safe amount to heat the supplemental 130

air to a correct temperature, but with respect to the essential principles of the invention it will now be clear that they may be incorporated in various different ways 5 and shapes.

I claim:

1. In an air heating furnace, the combination of a radiator comprising a horizontal ring-form flue having a downwardly opening gas inlet elbow at the center and an upward air passage between said flue and elbow, a fire chamber having a fuel feed conduit and a restricted gas outlet above the level of said conduit and of substantially 10 the same diameter as said elbow, a separately made, air-conducting ring interposed between and connecting the fire chamber outlet with said elbow inlet, an air supply duct open to atmosphere for admitting supplemental air to said ring and exit means in 15 the ring for delivering such air into the fire-gas flow in the ring connection.
2. In an air heating furnace, the combination of an enclosing outer casing having a panel front, a radiator therein comprising a horizontal ring-form flue having a gas outlet at one side, a downwardly open gas inlet elbow at its center and a space between 20 said flue and elbow forming an upward air passage, a fire chamber within the casing having a restricted gas outlet at its top and a fuel feed conduit extending laterally therefrom at a lower level and connected to 25 said panel front, a separately made, air-admission ring interposed between and connecting said restricted gas outlet to said radiator inlet and having an air supply duct 30 extending laterally therefrom to said panel front directly over said feed conduit, said duct and ring serving to heat and conduct supplemental air from the atmosphere and 35 deliver it to the fire gases flowing from the fire chamber to the radiator.
3. In an air heating furnace, the combination of a casing, a radiator therein comprising a horizontal, ring-form flue having a downwardly opening gas inlet elbow at the center and an annular air passage 40 between said flue and elbow, a fire chamber having an upwardly tapered dome terminating in a restricted gas outlet of substantially 45 the same diameter as said elbow and a separately made, hollow, air-admission ring forming the connection between said gas 50 outlet and said elbow inlet and of greater external diameter than either of them, said several parts being mutually organized and related to permit the upward air current rising around the fire chamber to flow freely 55 along said tapered dome and in cooling contact with the exterior of said hollow ring, and thence directly upwards through the air passage around said radiator elbow.
4. In an air heating furnace, the combination of an enclosing casing having a front, 60

a radiator therein comprising a horizontal ring-form gas flue having a downwardly open gas inlet elbow at its center and an annular space between said flue and elbow forming an upward air passage, a fire chamber within the casing having a tapered dome with a restricted gas outlet at its top of substantially the same diameter as said elbow and a fuel feed conduit extending laterally from said chamber, at a lower level to the furnace front, a separately made hollow, air-delivering ring connecting said restricted gas outlet to said radiator elbow and having an air supply duct extending laterally therefrom and connected with said front, the outer wall of said ring being disposed projecting into the air current upwardly flowing over said dome and around said radiator elbow.

5. In a furnace, the combination of a radiator comprising a horizontal ring-form gas flue having a central inlet elbow in the same plane as the flue and forming an annular air passage through the radiator, a fire chamber having a laterally extending fuel feed conduit and an upwardly tapered and restricted gas outlet connected to said elbow inlet above the level of said conduit supplemental air-admission means located at the connection of said parts and comprising an annular air passage having its outer wall vertically above the wall of the fire chamber and vertically below said annular radiator air passage and adapted to intercept the rising air current from said chamber through said annular passage.

6. In a furnace, the combination of an outer casing having a front, a radiator therein comprising a horizontal ring-form flue having a lateral cleaning-out entrance connected to an opening in said front and a central gas inlet elbow, said entrance flue and elbow all occupying a common horizontal plane and providing an upward air passage between the flue and elbow, a fire chamber having a restricted gas outlet at its top and a fuel feed conduit connected to said front, a separately made air-delivering ring interposed between and connecting said elbow inlet with the fire chamber outlet, and an air supply duct connecting said ring to an opening in the casing front and located beneath said cleaning-out entrance and above said fuel feed conduit.

7. In a furnace, the combination of a fire chamber having a main air entrance and an upward fire-gas outlet, a gas-conducting air-heating radiator connected to and above said outlet and supplemental air-admission means at the junction of said parts having a greater area for the delivery of air on one side of the gas flow than on the other.

8. In a furnace, the combination of a fire chamber having an upward fire-gas outlet, a return-flue radiator having a central

gas inlet part connected to said outlet and of substantially the same diameter as said outlet and air-admission means surrounding the junction of said parts having a greater air-delivering efficiency on one side of said junction than on the other, and disposed for contact with the upward air current from the fire chamber through the radiator.

10. In a furnace, the combination of a fire chamber having a main air entrance and a dome with a restricted fire-gas outlet at its top, a gas-conducting, air-heating radiator connected to said outlet and means for admitting supplemental air to the gas flow to the radiator having a greater area for delivery of said air on one side of the gas flow than on the other.

11. In a furnace, the combination of a fire chamber having a gas outlet, a gas-conducting radiator having an inlet elbow connected with said outlet and means for admitting supplemental air in the region of the junction of said parts having its greatest air-delivery area on the side toward which the elbow turns the gases in the radiator.

12. In a furnace, the combination of a fire chamber having a fuel feed doorway and a gas outlet, a gas-conducting radiator having an inlet elbow connected with said outlet and means for admitting supplemental air in the region of the junction of said parts having its greatest air-delivery area on the side adjacent said fuel doorway.

13. In a furnace, the combination of an air-heating radiator comprising a horizontal ring-form flue having a central inlet elbow, the space between said flue and elbow forming an air passage, a fire chamber having a restricted gas outlet of substantially the same diameter as said elbow and an air-admission means at the junction of the fire chamber and elbow having a greater air-delivery area on one side than on the other.

14. In a furnace, the combination of an air-heating radiator comprising a ring-form flue having a central inlet elbow, the space between said flue and elbow forming an upward air passage, a fire chamber having a restricted gas outlet of about the same diameter as said elbow, a separately made hollow, ring-form member constituting an admission means for supplemental air interposed between and supporting the radiator on the fire chamber, and connecting said outlet to the elbow inlet, the inner wall of said

member being provided with air exit means on the side thereof towards which the elbow turns the fire gases.

15. In a furnace, the combination of a radiator comprising a central inlet elbow and providing an upward air passage around the same, a fire chamber having a restricted gas outlet communicating with said elbow inlet, means for admitting supplemental air to said communication having greatest air-delivery area on the elbow side and an air supply duct connected to said member also on the elbow side.

16. In a furnace, the combination of a radiator comprising a horizontal, air-heating, ring-form flue having an inlet elbow at its center, both in substantially the same horizontal plane, the space between said flue and elbow forming an upward air passage, a fire chamber having a restricted gas outlet communicating with said inlet, a member for admitting supplemental air to said communication having greater air-delivery area on the side of the elbow connection to the ring-form flue than elsewhere, an air supply duct connected to said member on the side of maximum delivery area and a fuel feed conduit for the fire chamber situated at a lower level than said air duct.

17. In a furnace, the combination of a radiator comprising a horizontal ring-form flue having a central inlet elbow in the same plane as the flue and forming an upward air passage through the radiator, a fire chamber having a laterally extending fuel feed conduit and a restricted gas outlet connected to said elbow inlet above the level of said conduit, supplemental air-admission means in the region of said connection having more efficient air-delivery means adjacent the elbow connection to said flue than elsewhere and an air supply duct for said means connected to atmosphere.

18. In an air heating furnace, the combination of a radiator having a gas inlet, a fire chamber having a restricted gas outlet supporting said radiator and connected to the inlet thereof, an annular air passage surrounding the gases flowing from the chamber to the radiator, an air supply duct leading to said annular passage and a single delivery opening from said passage into the fire gas flow.

In testimony whereof, I have signed this specification.

DAVID M. MORPHY.
